Primary Examiner—Stacia Cadmus

(74) Attorney, Agent, or Firm—Curtis L. Harrington

(57) **CLAIM**

The ornamental design for a wheel, as shown and described.

DESCRIPTION

FIG. 1 is a front perspective view of the wheel; and, FIG. 2 is a front plan view of the wheel, it being understood that the ornamental design of FIGS. 1 and 2 are not expressed in top, bottom and side views and thus they are omitted, the circumferentially outwardly disposed areas of the inside of the rim is shown for illustrative purposes only and forming no part of the claimed design.
